UNITED STATES PATENT OFFICE.

WILFORD W. DAKE, OF GRAND HAVEN, MICHIGAN, ASSIGNOR TO PYLE NATIONAL ELECTRIC HEADLIGHT COMPANY, OF CHICAGO, ILLINOIS, A CORPORATION OF NEW JERSEY.

ELASTIC-FLUID TURBINE.

1,139,465.

Specification of Letters Patent. Patented May 11, 1915.

Application filed July 7, 1910. Serial No. 570,879.

To all whom it may concern:

Be it known that I, WILFORD W. DAKE, a citizen of the United States, and a resident of the city of Grand Haven, in the county 5 of Ottawa and State of Michigan, have invented certain new and useful Improvements in Elastic-Fluid Turbine-Engines, of which the following is a specification.

My invention relates to elastic fluid turbine engines, and its object is to provide such an engine improved as hereinafter set forth, and which shall be simple and economical in construction. This object is attained by, and my present invention is embodied in, the mechanism hereinafter described, illustrated by the accompanying drawings, in which:

Figure 1 is a vertical axial section of an elastic fluid turbine engine embodying my 10 improvements. Fig. 2 is a vertical section of certain parts (other parts being broken away), on line T—T of Fig. 1, being a plane at right angles to the plane of section on which Fig. 1 is taken, and illustrating the 15 passages by which the elastic fluid is delivered to the rotor, passes therefrom and is redelivered thereto, and passes therefrom and is redelivered thereto a second time; Fig. 20 3 is a bottom plan view of the primary passage block containing the passages through 25 which the elastic fluid is first received from the rotor and redelivered thereto, said block's supporting member being shown in section on the line of the arc K in Fig. 2; Fig. 4 is a top plan view of the nozzle block 30 35 through which such fluid is initially delivered to the rotor and of the secondary passage block containing the passages by which such fluid is secondarily received from the 40 rotor and again redelivered thereto, the supporting member of said nozzle and block being shown in section on the line of the arc L in Fig. 2; Fig. 5 is a side view of said 45 nozzle block, passage blocks, and their supporting member; Fig. 6 is a view in radial section of a portion, near its periphery, of the rotor body and of one of the rotor buckets carried thereby, together with part of the nozzle block and its supporting member; Fig. 50 55 Fig. 7 is a like view of part of said rotor body and of said rotor bucket, illustrating a preferred method of constructing the same; Fig. 8 is a perspective view of a series of three rotor buckets, the left-hand bucket

being shown in section; and Fig. 9 is a view 55 in perspective from a different direction, of one of said buckets.

A frame or casing 1 supported as by the feet 5 and having a cover 10 bolted thereto, incloses the operative parts of my turbine 60 engine. The rotor shaft 18 provided with a collar 72, has, toward its extremity, a tapering periphery, as shown in Fig. 1, on which is frictionally secured, as by the nut 78, the correspondingly bored hub of the rotor 65 body 19. A cylindrical portion 79 of the shaft, next its extremity, is provided with a sleeve 11, in which it is frictionally held and from which it may be withdrawn: the central bore of the cover 10 is fitted with a 70 removable hollow cylindrical member 12. In corresponding annular races 80³ in said sleeve and cylindrical member, roll the balls 81⁴ of the shaft's ball bearings. A suitable partition 16 and removable cover 13 form a 75 bearing oil chamber, to which oil may be supplied by removing the screw plug 15. It will be seen that by removing the cover 10, the ball bearings will be carried with it, including the sleeve 11, and that the 80 ball bearings, sleeve, etc., may be removed from the cover 10 by unscrewing the screws 14 and taking off the small cover 13.

On one face of the rotor body and at or near its periphery, are carried a series of 85 buckets 20, continuously arranged in a circle concentric with the rotor's shaft. These buckets are concaved forward, and their side walls diverge from their middle point outward each way at a corresponding angle, 90 as shown in Fig. 6, so that such diverging portion may coincide as nearly as may be with the sides (shown in dotted lines in said figure) of the jet of elastic fluid delivered to the buckets from either side. These 95 buckets are preferably stamped from sheet metal and are formed with wings 21, one on each side, for attaching them to the rotor body, which wings are adapted to be driven into two registering and concentric annular 100 grooves 82 in the rotor body, said grooves converging toward their bottoms, forming a dovetail, as shown. Fig. 7 illustrates the position of the parts at the beginning of the operation of attaching the buckets to 105 the rotor body; when the wings are driven into the grooves, being thus forced to converge, a retaining or tightening plug, in

form a continuous strip 22, serving for many or for all the buckets, is driven in beside the wings, thus firmly binding the buckets in place on the rotor body.

- 5 The elastic fluid, hereinafter for brevity, referred to as fluid, or as steam, enters as by the pipe 2, and is conducted by a suitable passage, as the circular passage 3 in the casing, whence it passes through an opening 3' 10 and a passage 51 into the recess 74 formed in the inner face of the retaining nut 56. The steam then passes through the holes 54 of the strainer 53, and through the passage 55 therein, whose lower extremity forms the 15 seat of the valve 57. It is thence discharged by suitable alining passages 52, as shown, into the passage 24 in the supporting member 23 which carries the passage blocks 27 and 31 and the nozzle block 26, and thence 20 into and through the nozzle 25. This nozzle may be divided, as shown in Fig. 2, by a partition 75, and delivers the steam to different buckets 76, 76' and 76''. After exerting this, its first driving impulse, on the 25 rotor, the steam emerges from such buckets into the passages 77, 77', 77'' of the primary passage block 27, when it is, by the curved partitions 78, 78', 78'' and 78''' redelivered to buckets at that time opposite the vents of such passages, as the buckets 79, 79' and 79''. After exerting this, its secondary driving impulse, on the rotor, the steam passes from such buckets into the passages 80, 80' and 80'' of the secondary passage block 31, when 30 it is, by the curved partitions 81, 81', 81'' and 81''', again redelivered to buckets at that time opposite the vents of such passages, as the buckets 82, 82', 82'' and 82''', and, after exerting this, its third impulse, escapes into 35 the exhaust chamber 4, whose walls aline with the path of the steam as it emerges finally from the buckets, and the steam is then carried off directly by the exhaust pipe 4' without entering the main chamber of 40 the casing. The curved arrows *a*, *b* and *c* in Fig. 2 indicate the path of the steam as above described. The passage blocks 27 and 31 are fastened to their supporting member 23 in any suitable manner, as by welding or riveting, or they may be integral therewith; and the nozzle block 26 may be attached to such member by screws 73 passing through such member and into the casing, thus 45 removably fastening such member and all said blocks in position. The various passages in the passage blocks are formed with walls contracting toward their discharge vents, as particularly shown in Figs. 3 and 4, and their intakes are wider and their discharge vents narrower than the buckets' openings registering therewith. A governor to control the valve 57 and regulate the supply of steam to the buckets comprises and is 50 operated by the following parts: When the centrifugal force becomes sufficient to over-

come the spring 36, governor bell-crank levers 38, pivoted at 38' on the rotor body, move the sleeve 35 along the rotor shaft 18, which such sleeve encircles, and, by the impinging of the end of such sleeve against 55 the thrust collar 41 bearing on the carbon washer 42, held in the non-rotating collar 43, moves said collar 43 axially the rotor shaft. This movement throws the lever 44, fulcrumed at 45 and pivoted at 46 to the 60 collar 43, which movement, through the anti-friction roller 47, operates the lever 48, fulcrumed at 49; and thus closes the valve 57, against the pressure of its spring 59 surrounding the valve stem 58, by bearing 65 against the adjusting nut 60, which may be locked in proper adjustment by the jam nut 61. The pressure of the spring 36, one end of which is fastened to the sleeve 35, and the other to the collar 43, is adjusted by 70 screws 39 threaded in such collar and journaled on the rotor body, such screws being held from accidental turning by their flat side heads being held in engaging recesses 75 40 in the face of the rotor body. The cage 80 50 of the valve 57 is formed of a separate piece from the casing or frame of my engine, is conical in shape, as shown, and is adapted to tightly fit in a corresponding recess in such casing, in which it is securely 85 held as by the retaining nut 56, but may be readily removed to effect repairs, cleaning, etc.

A governor emergency brake to check the speed of the rotor, is composed of, and operated by, the following parts: A brake shoe 65 adapted to frictionally bear on the periphery of an interior circle 6 of the casing, concentric with the shaft, is carried by a rod slidably radially in bearings on the rotor. When the centrifugal force becomes sufficient to drive the inclined face of the lug of the brake shoe out of the holding engagement of the leaf spring 66 (whose pressure may be regulated by a suitable set screw 70 100 67 locked in desired adjustment by a lock-nut 68), the brake shoe will frictionally and operatively engage the circle 6. When the centrifugal force sufficiently diminishes, the spring 69, pressing on the thrust collar 66 105 110 will withdraw the brake shoe, and the spring 66 will again engage and hold the lug. It will be seen that the brake shoe is thus positively retained in an entirely inoperative position until the centrifugal force is sufficient to carry its lug out of engagement 115 120 with the leaf spring.

Other parts are illustrated in the drawings and are indicated by the following reference characters, viz.: 7 indicates an internal rib 125 in the casing, operating to strengthen the same and to confine lubricating oil 92, as shown, in the oil chamber 8. The vapors in the casing chamber, stirred by the motion of the running parts of my engine, take up 130

this oil, and thus such parts contained in said chamber are constantly lubricated. 9 is a drain hole in the casing. 17 is a screw plug closing an opening in the casing cover 5 through which the screws 39 may be adjusted. 23' is a removable thin sheet of metal held between the nozzle block and its supporting member to receive the wearing action of the steam jet. 62 is a passage leading 10 from passage 51 to the rear of the valve 57 for the purpose of admitting steam to balance the pressure of the steam on the face of the valve. The area of the face and of the rear of the valve on which the steam 15 presses is normally equal. 63 is a screw plug closing an oil hole.

Certain features herein described and shown in the drawings are made the subjects-matter of my other copending applications for patent, viz.: Ser. No. 599,280 filed Dec. 27, 1910; Ser. No. 604,085 filed Jan. 23, 1911 and Ser. No. 604,086 filed Jan. 23, 1911.

My invention may manifestly be embodied in varying mechanisms without departing 25 from its spirit; and I do not propose to confine myself to the construction shown and described.

The buckets with their curved front and rear walls and peculiarly shaped sides are in 30 effect of approximately uniform cross-sectional area, for the bucket sides diverge outwardly in both directions from the middle, whereas the curved front and rear walls converge outwardly from the middle of the 35 bucket. In any event the bucket mouths are diverging. Passages in the passage blocks are shaped so that they are relatively wide at their inlets and relatively narrow at their outlets or nozzle ends. The result is that 40 when the buckets and passage blocks are brought together as indicated, the fluid or steam is discharged from the passage nozzle into a relatively wide bucket opening and it is discharged from the bucket into 45 an opening larger than that of the bucket.

I claim—

1. In a machine of the character described, a rotor having a continuous series 50 of rotor buckets, and a passage block having a passage through which the driving fluid is redelivered from and to the rotor buckets in said series, said passage at its intake being wider, and at its discharge vent narrower, respectively than the discharge vent and intake of the buckets, the direction of said passage being in a plane at right angles to the 55 rotor's axis.

2. In a machine of the character described, a rotor having a continuous series 60 of rotor buckets, and a passage block having a passage through which the driving fluid is redelivered from and to the buckets in

said series, and which passage is narrower at its discharge vent than the intake of the buckets, the direction of said passage being 65 in a plane at right angles to the rotor's axis.

3. In a machine of the character described, a rotor having a continuous series of rotor buckets, and a passage block having a passage through which the driving fluid is redelivered from and to the buckets in 70 said series and which passage is wider at its intake than the discharge vent of the buckets, the direction of said passage being 75 in a plane at right angles to the rotor's axis.

4. In a machine of the character described, a series of buckets mounted on a rotor, said buckets provided with front and rear walls which converge from their middle outwardly and with side walls which 80 diverge from their middle outwardly.

5. In a machine of the character described, a series of buckets mounted on a rotor, said buckets provided with front and rear walls which converge from their middle outwardly and with side walls which 85 diverge from their middle outwardly and passage blocks provided with nozzles narrower than the receiving end of said buckets.

6. In a machine of the character described, the combination of a rotor with a series of radial flow buckets mounted thereon and passage blocks on opposite sides of the buckets provided with passages whose discharge nozzles are narrower and whose inlet 90 openings are wider than the respective opposed openings of the buckets.

7. In a machine of the character described, the combination of a rotor with a series of buckets mounted thereon and passage blocks on opposite sides of the buckets provided with passages whose discharge nozzles are narrower and whose inlet openings are wider than the respective opposed openings of the buckets, said buckets provided 100 with separate walls which respectively converge and diverge in pairs from the middle of the bucket outwardly.

8. In a machine of the character described, a rotor in combination with a series 110 of radial flow buckets mounted thereon and passage blocks for the fluid on opposite sides of the rotor buckets, said rotor buckets of approximately uniform cross sectional area, and said passages shaped so that their discharge openings are wider than the 115 bucket outlets.

In witness whereof, I have signed my name to this specification in the presence of two subscribing witnesses.

WILFORD W. DAKE.

Witnesses:

WILLIAMENA C. YOUNG,

ANNA BOTTJE.
